UNITED STATES PATENT OFFICE

2,145,205

CIGAR LIGHTER

Gustave F. Bahr, Fairfield, Conn., assignor to
 Casco Products Corporation, Bridgeport, Conn.,
 a corporation of Connecticut

Original application November 13, 1935, Serial
 No. 49,542. Divided and this application Octo-
 ber 9, 1936, Serial No. 104,746

5 Claims. (Cl. 219—32)

This invention relates to electric cigar lighters, and more particularly to the heating elements or resistance coil units of such devices.

This application is a division of my copending application S. N. 49,542, filed November 13, 1935.

An object of the present invention is to provide an improved heating element unit for a cigar lighter, which permits of quick and easy removal and replacement. This is accomplished by providing 10 the heating element unit with an improved attaching and positioning means.

In the embodiment of the invention shown herein this improved means for permitting quick and easy removal and replacement of the heating element unit comprises a split pin adapted to frictionally engage a cooperating socket structure of the supporting device, and a plate carried by the pin, and having wings or lugs adapted to enter recesses in the supporting device.

20 Further objects and advantages will herein-after appear.

In the accompanying drawing, illustrating an embodiment of the invention:

Figure 1 shows the present improved heating element as incorporated in a cigar lighter of the removable igniting unit type. In this figure, the holder and removable igniting unit of the lighter are shown in axial section.

Fig. 2 is a side elevation of the heating element per se, with a fragmentary portion thereof shown in section.

Fig. 3 is a face or left-end view of the element of Fig. 2.

Fig. 4 is a rear or right end view of the element of Fig. 2.

The present invention is applied to a cigar lighter, as illustrated in the accompanying drawing, which comprises an igniting unit 10 removably mounted on a holding device 11. The latter has a hollow metal sleeve 12, having spring tongues 13 normally biased outwardly to resiliently hold the igniting unit, and which tongues extend longitudinally of the sleeve 12, and are disposed so that those adjacent each other extend in opposite directions, all as in the patent to Joseph H. Cohen, No. 2,035,864, dated March 31, 1936, in which this feature is claimed.

The sleeve 12 has an internal flange 14 at its rear end, which is tightly clamped to a metal escutcheon 15 adapted to engage an instrument board or other support. The flange 14 and the escutcheon 15 are clamped together by recessed washers 16 which in turn are clamped against a shoulder 17 of a nipple 18, the end of said nipple being headed over on

55 said washers for this purpose. A nut 19 and

lock washer 20 are carried on the threaded portion of the nipple 18, and serve to securely draw the escutcheon 15 against the automobile instrument board or other supporting surface, and to securely support the holding device 11 thereby, 5 and also to make grounded electrical connection thereto. Passing through the nipple 18 is a pin 21 which is insulated from the nipple by an insulating washer 22 and an insulating sleeve 23. An integral collar 24 on the pin 21 bears against the 10 insulating washer 22 and prevents the pin from being drawn through the nipple. The other end of the pin passes through insulating washers 25 and a contact disk 26, and is headed over on the latter so as to hold this firmly against the end 15 of the nipple 18 but insulated therefrom. The disk 26 has obliquely extending curved wings 26a which adapt it to engage and electrically connect with a heating element contact to be hereinafter described. The pin 21 extends back- 20 wardly beyond the integral collar 24, and is recessed to receive the bare end and part of the insulation of a conducting wire 27, which is preferably sweated in said pin with solder. A soft rubber sleeve 28 is slipped over the exposed parts 25 of the pin 21 to preclude the possibility of a short-circuit occurring at this place.

The disk 26 forms, by virtue of its connection to the wire 27, an electrical contact for engagement with the igniting unit now to be described, 30 and the sleeve 12, being grounded on the instrument board, serves as a contact for the return circuit.

The removable igniting unit 10 comprises a cylindrical body 29 having a stepped bore 30 and 35 31, with a shoulder 32. The bore 30 is of a size to slip closely over the sleeve 12 of the holding device, and therefore the tongues 13 of the sleeve 12, which are normally biased outwardly, engage with the bore 30 of the body and provide for 40 yieldingly holding the igniting unit 10 on the holding device 11.

According to the present invention there is provided, to be carried by the igniting unit, an improved heating element adapted to be attached 45 to and carried by said unit so that it can be quickly and easily removed therefrom and replaced without the use of special tools and without a great degree of skill on the part of the operator. Also said heating element is adapted 50 to engage and contact with the disk contact of the holding device.

As shown in Figs 2, 3, and 4, the embodiment of this improved heating element, designated by the numeral 33, includes a metal cup or carrier 55

34 and a central slotted attachment prong or stud 35 firmly connected with the cup and adapted to support same. The cup 34 is relatively shallow, having cylindrical walls 34a and a circular bottom 34b, and the walls being turned inwardly at the brim of the cup to provide an internal flange 34c. The cup 34 encloses and carries a spirally wound resistance wire or ribbon 36 the convolutions of which are spaced from the 10 cup bottom, said coil having its outer end connected at 37 to the wall 34a and having its inner end firmly gripped in a slotted head 38 of the prong 35 (see Fig. 3). Preferably the heating coil 36 has its ends welded to the cup 34 and 15 head 38 of the stud or prong respectively, as disclosed and claimed in the application of Joseph H. Cohen, Serial No. 36,683, filed August 17, 1935. The bottom 34b of the cup is centrally apertured to permit the prong 35 to pass therethrough, said prong being insulated from the 20 cup by an insulating washer 40 and a similar but smaller washer (not shown) disposed between the head 38 and the inside of the cup bottom.

Thus the prong 35 is securely connected with 25 the cup 34 but insulated therefrom, and said stud serves not only to securely support the cup in firm, properly aligned position, but also serves as an electrical connection to the inner end of the heating coil 36. As shown, the prong 35 is cut 30 or slotted for a portion of its length, providing resilient tines 35a which are biased outwardly slightly to secure firm engagement with the socketing means on the igniting unit. The cup 34 is also adapted to serve as an electrical contact 35 for conducting current to the outer end of the heating coil, and in this respect the outer surface of the flange 34c serves to engage the wings 26a of the disk contact of the holder.

For the purpose of engaging the prong 35 to 40 support the heating element upon the igniting unit, and for connecting with the heating coil, the igniting unit is provided with a cylindrical metal sleeve 41 supported at the forward or front end of the body 29 on the shoulder 31 thereof, 45 said sleeve having an annular flange 42 crimped therein to engage said shoulder, and the end of the sleeve being spun over to permanently secure said engagement. The rear of the sleeve 41 has an end wall 43 apertured at its center and supporting a metal tube 44 by means of flanges of said tube engaging the opposite sides of the end. The tube 44 extends forwardly into the sleeve 41, being concentrically located relatively thereto, and said tube has an internal diameter of a size 50 to closely receive the stud 35 and frictionally hold same by virtue of the outwardly biased tines 35a thereof, so that the heating element can be firmly supported at the rear of the igniting unit 10, and in true axial alignment therewith.

60 Thus there is provided by the present invention a frictionally mounted heating element 33 for the igniting unit 10 which can be rapidly and easily removed, and yet which is securely held in true axial alignment and in firm position at the 65 rear of the body 29. It is only necessary, in order to easily remove the element 33, to hold the body 29 in one hand and apply a prying tool underneath the edge of the metal cup 34 so as to force the element outward. Instead of a prying tool a 70 key, or a button hook may be used, or the cup can be grasped directly with the fingers. If desired, pressure may be applied to the end of the prong 35 by means of a matchstick, toothpick or the point of a refillable pencil until the heating 75 element is ejected.

In connection with this latter operation, the body 29 of the igniting unit has a removable end closure 45 carried by a metal thimble 45a which is frictionally held within the sleeve 41. The closure 45 and thimble may be readily removed by prying same out with a pointed implement such as a knife blade or a nail file, in order to gain access to the end of the prong 35. 5

The igniting unit 10 is normally held in inoperative position on the holder 11, as shown in 10 Fig. 1, by a dished ring 46 and a spring 47, both carried on the sleeve 41. The spring 47 bears against the shoulder 42 and against the ring 46, and yieldingly urges these apart, the latter being retained on the sleeve 41 by integral fingers 15 lanced outwardly from said sleeve. The ring 46 is adapted to engage the end of the sleeve 12 of the holder 11, thereby forming a yieldable stop when the igniting unit 10 is slipped on said holder, and maintaining the heating element out 20 of contact with the disk 26, and therefore in unenergized condition. The ring 46 and spring 47 also serve as an electrical connection between the grounded sleeve 12 and the sleeve 41.

When it is desired to use the cigar lighter, the 25 igniting unit 10 is depressed inwardly against the action of the spring 47 so that the cup 34 of the heating element engages the contact disk 26. The igniting unit is held in this position, and current is conducted through the wire 27, pin 21, disk 30 26, cup 34, heating coil 36, prong 35, sleeve 44, sleeve 41, ring 46, and thence through the sleeve 12 to the grounded circuit. Energization of the heating coil 36 as just outlined will cause it to become hot, or perhaps incandescent, when it is 35 ready for use.

In the event that the heating coil is energized to become incandescent, light from this incandescence may be used to apprise a user of the 40 readiness of the unit, and for this purpose the end closure 45 is made of an illuminable or translucent material to constitute a lens, the end 43 of the sleeve 41 is apertured, and the bottom 34b of the cup 34 is also apertured as shown in Figs. 3 and 4. Thus light from the heating coil 36 will 45 strike the lens member 45 and illuminate same. Of course, the apertures in the bottom of the cup 34 must be properly aligned with the apertures of the end 43 of the sleeve 41.

In order to provide for proper alignment of the 50 apertures of the cup and sleeve so that light from the heating coil may pass therethrough there is provided by the present invention a positioning means associated with the cup 34 in a predetermined relation thereto, and in the embodiment 55 shown this means comprises a washer 48 carried by the prong 35 and firmly attached thereto, said washer having a plurality of rearwardly extending wings 49 adapted to enter the apertures of the end 43 of the sleeve 41. The wings 49 by reason 60 of their engagement with the sides of the apertures of the sleeve 41, prevent relative turning between the heating element 33 and the igniting unit 10, and said wings are so disposed that, when 65 extending into said apertures, they correctly position the heating element so that the apertures of the cup 34 are in proper alignment to permit light to pass through to the lens 45.

Thus the heating element is positioned on the 70 igniting unit 10 in a simple and positive manner, 75 and in manner such that an inexperienced person can correctly replace the heating element on the igniting unit without difficulty.

The means for positioning the heating element 75 relatively to the igniting unit also serves an addi- 75

tional useful purpose. At times the contacting surfaces of the cup 34 and the disk 26 may become dirty so as to impair the electrical connection between these surfaces. In such event, it is merely necessary to depress the igniting unit 10 and turn said unit so depressing it, in order to clean these contacting surfaces, since turning of the igniting unit will result in turning of the cup 34 so as to scrape against the contact disk 26.

10 It will be noted that the prong 35 for supporting the heating element is centrally located relatively to the cup 34 and positioning means 48 and 49, these being symmetrically disposed relative to the prong 35, and this arrangement provides for extremely simple and mistake-proof replacement 15 of a heating element on the igniting unit. Also, effective electrical connection is maintained between the prong 35 and the supporting structure of the igniting unit because of the relatively large 20 surface of said prong and the firm engagement thereof with the sleeve 44. The heating element is also firmly held in aligned position because of the elongate nature of the prong 35, and this is important in providing for uniform and well distributed contact between the cup 34 and the disk 25 26 when the igniting unit is depressed on the holder.

Variations and modifications may be made within the scope of this invention and portions of the improvements may be used without others.

30 I claim:

1. In a device of the type described, a heating member adapted to be frictionally mounted on an igniting unit comprising a contacting cup; a pin projecting rearwardly through said cup and insulated therefrom; guide means including a transversely extending member mounted on said pin having rearwardly extending guide members thereon, said guide members being in spaced parallel relation with said pin; and a heating coil 40 disposed in said cup.

2. A cigar lighter heating element to be mounted on an igniting unit comprising a cup having electrical contacting means on the outer surface thereof; electrical heating means disposed in said 45 cup; a mounting pin having an end secured to the heating means and passing through the bottom wall of said cup; and a plate carried by the pin,

said plate lying substantially parallel to the bottom wall of said cup and having lugs projecting laterally thereof and away from said cup, said lugs interlocking with means on the igniting unit to prevent rotation of the heating element when mounted in a predetermined position on the igniting unit. 5

3. In a device of the type described, a heating member adapted to be frictionally mounted on an igniting unit comprising a contacting cup; a 10 mounting pin projecting rearwardly from said cup; a washer having rearwardly extending guide means mounted on said pin, said means extending substantially parallel to but spaced from said pin; and a heating coil disposed in said cup with one 15 end secured to the front of said pin and having the other end in electric contact with the cup.

4. In a device of the type described, a heating member adapted to be frictionally mounted on an igniting unit provided with light passages comprising a contact cup having light apertures formed in a wall thereof; a pin projecting rearwardly through the wall of said cup but insulated therefrom; guide means including a transversely extending member mounted on said pin having 20 rearwardly extending guide members thereon, said guide members being in spaced parallel relation with said pin and adapted to engage means on the igniting unit to locate the cup in a predetermined position on said unit and to align the 25 apertures of said cup with the light passages of the unit; and a heating coil disposed in said cup.

5. In a device of the type described, a heating member adapted to be frictionally mounted on an igniting unit comprising a contacting cup; a pin 35 projecting rearwardly through said cup but insulated therefrom; a washer mounted on said pin adjacent said cup and lying substantially parallel to the bottom wall thereof, said washer having laterally extending guiding and positioning lugs 40 projecting rearwardly away from said cup; and a heating coil disposed in said cup, said cup having spaced apertures through which light emanating from the heating coil may pass when the heating member is positioned on the igniting unit by said 45 lugs.

GUSTAVE F. BAHR.
